INSECTICIDE

Carl P. Hopkins, Grand Junction, Colo., assignor
to The Latimer-Goodwin Chemical Company,
Grand Junction, Colo., a corporation of Colo-
rado

No Drawing. Application April 15, 1935,
Serial No. 16,408

8 Claims. (Cl. 167—33)

In insecticides for application as sprays, it has been customary to embody an oil such as petroleum, fish oil, or oleic acid. These materials have certain disadvantages which limit their use, being either directly injurious to leaves and plant tissue, or on fruit surfaces causing the insecticide poison to adhere so tightly that it can be removed only with the greatest difficulty, even in chemical baths such as warm acid or alkali. When drastic cleaning operations are thus required, the fruit so treated is found to deteriorate in storage. In accordance with the present invention however, a composition now becomes possible which obviates these disadvantages, and also provides a spray of a much greater effectiveness than heretofore.

To the accomplishment of the foregoing and related ends, the invention, then, comprises the features hereinafter fully described, and particularly pointed out in the claims, the following description setting forth in detail certain illustrative embodiments of the invention, these being indicative however, of but a few of the various ways in which the principle of the invention may be employed.

In the preparation of an insecticide in accordance with the invention, I make up an emulsion of a nitrogenous oily base. This may be such nitrogenous oils as contain the pyridine or quinoline radicals, for instance pyridine, pyridine homologs having alkyl radicals attached, as methyl, ethyl, etc., quinoline, and the like, etc. These are slightly basic in character, and are obtained by the destructive distillation of coal, shale, etc. They may also be made synthetically. Nitrogenous oils obtained from coal, oil shale, and from synthetic derivation are applicable generally, but the oil particularly preferred for my purpose is a distillation cut ranging from 520° to 725° F. With the nitrogenous oil is also incorporated an insect poison, as an arsenic compound or an organic poison, or both; arsenates of lead, calcium, etc., pyrethrum, helebore, nicotine, derris, cube, cracca, rotenone, etc., being of particular importance. The nitrogenous oily base is emulsified by a suitable emulsifying agent, as for instance casein, triethanolamine oleate, diglycol oleate, etc.

As an example: Pyridine is emulsified with triethanolamine oleate to an 80 per cent emulsion, and lead arsenate is incorporated at the rate of 4 pounds per gallon of pyridine.

As another example: A coal tar crude pyridine distillation fraction boiling between 520° and 725° F. is emulsified with casein, and lead arsenate incorporated at the rate of 4 pounds per gallon of the pyridine distillation fraction, and $\frac{1}{3}$ pound of casein.

As another example: A crude pyridine distillation fraction boiling in the range of 520° to 725° F. is emulsified with triethanolamine oleate, and

nicotine is incorporated in amount to provide a proportion of 1:1500 of nicotine and 1 per cent of nitrogen oily base in the emulsion as diluted for spray-application.

As instancing the effectiveness of my composition in depositing arsenic on the surface being sprayed, the following comparisons may be noted:

	100 gals. spray mixture	Total de- posit in mmg. As ₂ O ₃ per sq. in.
No. 1.....	Summer oil emulsion, $\frac{3}{4}$ gallon; lead arsenate, 3 pounds.	38.3 15
No. 2.....	Summer oil emulsion, $\frac{3}{4}$ gallon; lead arsenate, 3 pounds; casein spreader, $\frac{1}{4}$ pound.	34.4
No. 3.....	Nitrogenous oil, $\frac{1}{2}$ gallon; lead arsenate, 2 pounds.	87.2
No. 4.....	Nitrogenous oil, $\frac{1}{2}$ gallon; lead arsenate, 2 pounds; casein spreader, $\frac{1}{4}$ pound.	62.6 20

The summer oil emulsion is that in accordance with the recommendations in the report of the Western Cooperative Oil Spray Project Conference, 1934, and the same precision spray machine was used in all cases, and applied at equal rates to beeswax-coated surfaces in simulation of the wax-surfaces encountered in apples being sprayed.

Although 50 per cent more lead arsenate was used with the petroleum emulsions Nos. 1 and 2 above than with the nitrogenous oils of the present invention as in Nos. 3 and 4, there was an arsenate deposit in employing No. 3 which amounts to a 127 per cent increase over No. 1. And No. 4 shows an 82 per cent increase in arsenate deposited, as compared with No. 2, the petroleum emulsion composition. Authorities are agreed that insect control is in direct proportion to arsenic deposit.

Again, as instancing the remarkable effectiveness of my composition with organic poisons, the following may be noted as comparative tests on mealy bugs in greenhouse practice:

	Composition	
No. 1.....	Petroleum oil emulsion 1 per cent, and 40 per cent nicotine 1:1500.	50 per cent destruc- tion.
No. 2.....	Pyridine base oil emulsion 1 per cent, and 40 per cent nicotine 1:1500.	95 per cent destruc- tion.

Employing the pyridine composition No. 2 just mentioned as a spray for red spider on apple trees, it was found that 95 per cent of the pests were dead in twenty-four hours, whereas the petroleum composition was ineffective. Using a spray mixture with the same amount of nicotine as No. 2, but only $\frac{1}{2}$ per cent pyridine base oil 60

emulsion, as a spray for wooly aphis, a clean-up of nearly 100 per cent was shown.

- Not only are spray compositions in accordance with the present invention more effective, but it is found that spray residue on apples and the like can be removed much more readily for marketing, than is possible with standard insecticides heretofore employed. In current packing house practice, apples and other fruits are put through washers employing acid solutions for dissolving the spray residue arsenate. Comparative results are shown with this material, operating for removal of spray residue from a typical petroleum spray and the present improved compositions, as follows:

	Spray composition	Spray-residue washing solution	As ₂ O ₃ left
20	Lead arsenate 3#/100 plus summer oil emulsion, 3/4 gal./100.	1 1/2% HCl at 110° F.—2 minutes.	2.1 mmg. per square inch.
	Lead arsenate 3#/100 plus miscible nitrogen base oil, 3/4 gal./100.	----do-----	1.7 mmg. per square inch.
25	Lead arsenate 3#/100 plus miscible nitrogen base oil 1/2 gal./100.	----do-----	Trace.

To some extent also, silicate of soda is used instead of acid as solvent for the residual arsenate, and comparative results are also shown with this wash.

	Spray composition	Spray-residue washing solution	As ₂ O ₃ left
35	Lead arsenate 3#/100 plus summer oil emulsion, 3/4 gal./100.	Sodium silicate 1 lb. per gal. at 120° F.—2 minutes.	2.8 mmg. per square inch.
40	Lead arsenate 3#/100 plus miscible nitrogen base oil, 3/4 gal./100.	----do-----	0.9 mmg. per square inch.
	Lead arsenate 3#/100 plus miscible nitrogen base oil 1/2 gal./100.	----do-----	0.46 mmg. per square inch.

- 45 Particularly noteworthy is the fact that compositions in accordance with the present invention are not only effective and easily removed in washer installations for elimination of residues on fruit being prepared for market, but no injurious action on leaf surfaces or vegetation is had as

in the case of petroleum sprays now in widespread use.

Other modes of applying the principle of the invention may be employed, change being made as regards the details described; provided the features stated in any of the following claims, or the equivalent of such, be employed.

I therefore particularly point out and distinctly claim as my invention:-

1. An insecticide, comprising an insect poison, 10 and a carrier which renders deposits thereof easily removable, said carrier containing as an essential ingredient an emulsified unneutralized heterocyclic nitrogenous oily base.

2. An insecticide, comprising an insect poison, 15 and a carrier which renders deposits thereof easily removable, said carrier including as an essential ingredient emulsified unneutralized pyridine.

3. An insecticide, comprising an insect poison, 20 and a carrier which renders deposits thereof easily removable, said carrier including as an essential ingredient emulsified unneutralized alkyl pyridine.

4. An insecticide, comprising an insect poison, 25 and a carrier which renders deposits thereof easily removable, said carrier including as an essential ingredient emulsified unneutralized quinoline.

5. An insecticide, comprising lead arsenate, 30 and a carrier which renders deposits thereof easily removable, said carrier including as an essential ingredient an emulsified unneutralized heterocyclic nitrogenous base.

6. An insecticide, comprising lead arsenate, 35 and a carrier which renders deposits thereof easily removable, said carrier including as an essential ingredient emulsified unneutralized pyridine.

7. An insecticide, comprising lead arsenate, 40 and a carrier which renders deposits thereof easily removable, said carrier including as an essential ingredient emulsified unneutralized alkyl pyridine.

8. An insecticide, comprising lead arsenate, 45 and a carrier which renders deposits thereof easily removable, said carrier including as an essential ingredient emulsified unneutralized quinoline.

CARL P. HOPKINS. 50
